UNITED STATES PATENT OFFICE

WARREN NOBLE, OF DETROIT, MICHIGAN, ASSIGNOR TO ELECTROMASTER, INC., OF DETROIT, MICHIGAN, A CORPORATION OF MICHIGAN

DESIGN FOR AN ELECTRIC STOVE OR SIMILAR ARTICLE

Application filed April 11, 1930. Serial No. 35,222. Term of patent 7 years.

To all whom it may concern:

Be it known that I, WARREN NOBLE, a citizen of the United States, and a resident of the city of Detroit, in the county of Wayne and State of Michigan, have invented a new, original, and ornamental Design for an Electric Stove or Similar Article, of which the following is the specification, reference being had to the accompanying drawing, forming a part hereof.

On the drawing:

I claim:

The ornamental design for an electric stove, or similar article, as shown.

WARREN NOBLE.
